UNITED STATES PATENT OFFICE.

ALEXANDER ALBERT HOLLE, OF WESTMINSTER, LONDON, ENGLAND.

AEROFOIL FOR AEROPLANES.

1,379,921.

Specification of Letters Patent. Patented May 31, 1921.

Application filed August 11, 1919. Serial No. 316,919.

To all whom it may concern:

Be it known that I, ALEXANDER ALBERT HOLLE, a subject of the Queen of the Netherlands, residing at 19 Half Moon street, in the city of Westminster, administrative county of London, have invented certain new and useful Improvements in Aerofoils for Aeroplanes, of which the following is a specification.

10. This invention relates to the wings or aerofoils of aeroplanes and has for its object to obtain automatic longitudinal stability under variations of the angle of incidence relatively to the air without the use of small auxiliary aerofoils or the like.

The longitudinal instability of a cambered aerofoil arises from an unstable variation of the distribution of pressure due to the changes in the level or angle at which 20 the air is divided at the leading edge of the aerofoil or from a combination of both changes, and to the formation—at all angles but the one to which the curvature of the aerofoil is best suited—of a region of “dead air” which constitutes what is in effect an artificial extension of the nose of the aerofoil, which gives rise to an alteration in the air flow. For instance, at lesser angles than the optimum angle for the curvature, as 30 when struck by a downward gust or when the angle of flight is accidentally reduced from any cause, the air flow is divided at a point above and in front of the leading edge of the aerofoil, and inversely when struck by an upward gust or when the angle of flight is accidentally increased, the air flow is divided at a point below the leading edge. In the former case the “dead air” nose, as I 40 will term it, extends above the leading edge and presents a flatter angle of entry to the air flow, which causes the air to strike the aerofoil at a lesser angle where the degree of curvature of the aerofoil is less than at the leading edge. This creates a less intensive vacuum and causes a considerable portion of the upper surface of the aerofoil adjacent to its leading edge to be under a positive downward and backward pressure, which results in the center of pressure moving 45 nearer to the trailing edge of the aerofoil. In the latter case, when the angle is greater than the optimum angle for the curvature, the “dead air” nose extends below the leading edge of the aerofoil and the 50 air flow is directed upward at a steeper angle

which brings the center of pressure more forward.

By controlling this “dead air” nose by reducing or regulating or by both means combined the heaping up of air at the leading 60 edge of the aerofoil a stable variation of the distribution of pressure can be obtained. In addition to which it makes it possible to adopt a single spar system of construction for the aerofoil.

I attain the object of this invention by making the leading or forward part of the aerofoil flexible in such a manner that, when the leading edge is under excessive downward pressure the nose or leading edge 65 flexes downward and slightly rearward whereby the camber of the upper surface increases and the concavity of the under surface decreases so that the angle of entry becomes steeper and the stratum of air swept 70 by the aerofoil is divided at a lower level, and inversely, when said nose or leading edge is under excessive upward pressure, said nose or leading edge flexes upward and slightly forward whereby the camber of the 75 upper surface decreases and the curvature of the under surface of the leading part is increased so that the angle of entry becomes flatter and the stratum of air swept by the aerofoil is divided at a higher level which 80 results in the “dead air” formation under the leading edge being reduced.

In order that this invention may be fully understood I will more particularly describe it making reference to the accompanying drawing in which:—Figures 1, 2 and 3 are diagrammatic views in cross section of an aerofoil constructed according to the present invention, Fig. 1 showing the leading edge in its normal position under load, 90 Fig. 2 showing the leading edge under the influence of excessive upward pressure, and Fig. 3 showing the leading edge under the influence of a maximum of excessive downward pressure, and Figs. 4 and 5 are broken 95 views in side elevation and plan respectively showing—by way of example—one method of carrying this invention into practice.

Throughout the views similar parts are marked with like letters of reference.

According to the present invention the forward part *x* of the aerofoil is made flexible within certain limits the upper surface being cambered in the usual manner and the under surface when the aerofoil is not un- 110

der load being also slightly cambered *i. e.* of slightly convex form. When the aerofoil is under load the convexity of the under surface becomes a concavity and when 5 there is excessive pressure above its nose or leading edge x^1 it will be deflected downward and slightly rearward which will increase the camber of its surface and decrease the concavity of its under surface, 10 and when there is excessive pressure under its nose or leading edge it will be deflected upward and slightly forward which will decrease the camber of its upper surface and increase the curvature of its under surface 15 at its leading part, the result being that the forward motion of the wing will give it its optimum shape by reason of the pressure distribution resulting from the forward motion of the correct angle. It will be ap- 20 preciated that during excessive downward pressure the concavity of the under surface of the forward part will gradually dis- appear and become convex as shown in Fig. 3 due to the increased negative pressure 25 created under it.

In the construction shown in Figs. 4 and 5 the main part x^2 of the aerofoil is of the usual rigid construction and the element a forming the nose of the leading part x^1 of 30 the aerofoil is supported by a series of elastic elements b carried either by the main spar y as shown, or to the longitudinal ribs or formers z , the upper surface v being supported by means of a series of flexible mem- 35 bers c which extend between the main spar and the element a to both of which they are fixed and the under surface w being supported by means of a series of flexible members d which extend between said main 40 spar y and said element a being fixed to the latter and free to slide in relation to the former. The shape of the members c and d is such as to make the upper and under surfaces of the leading or forward part x 45 conform to the general curvature of the aerofoil when flying at the normal angle of incidence and under normal load.

To limit the movements of the elastic elements b and therefore the degree of flexi- 50 bility of the leading edge stops such as e , e are provided which can conveniently be carried by the adjacent longitudinal ribs or formers z . When it is desired to vary the degree of flexibility of the elastic members 55 b during flight the positions of the stops e are made adjustable in relation to said members by means of any suitable mechanical device.

It will be appreciated that the difference 60 between the stability afforded by the present invention and that of the hitherto known stable wing is that in said known type of stable wing in which the instability over different portions are made to negative each 65 other's action there is a constant torsional

stress in the wing tending to deform the wing, while in a wing constructed according to the present invention there is an anti-torsional stress generated as soon as the pressure distribution varies owing to 70 changes in the angle of incidence which tends to preserve the shape of the wing and relieves the spar of any torsional stress which makes for simplification of design and reduction of weight. 75

I claim:

1. In an aerofoil for aeroplanes, the combination of a rigid main part which comprises a main spar, a series of rigid ribs or formers carried by said spar the forward ends of which do not extend as far as the nose or leading edge, and covering surfaces carried by said ribs or formers and extending between said main spar and the rear or trailing edges; and a flexible forward part 30 comprising a series of elastic members carried by the main spar, a rigid nose carried by said elastic members, a series of flexible elements extending between and carried by the main spar and the nose, a series of flexible elements carried by the nose and extending between said nose and said main spar, and covering surfaces carried by said flexible elements. 35

2. In an aerofoil for aeroplanes, the combination of a rigid main part which comprises a main spar, a series of rigid ribs or formers carried by said spar the forward ends of which do not extend as far as the nose or leading edge, and covering surfaces 100 carried by said ribs or formers and extending between said main spar and the rear or trailing edge; and a flexible forward part comprising a series of elastic members carried by the main spar, a rigid nose carried by said elastic members, a series of flexible elements extending between and carried by the main spar and the nose, a series of flexible elements carried by the nose and extending between said nose and said main spar, and covering surfaces carried by said elements; and means for limiting the 105 amount of movement of the elastic members. 110

3. In an aerofoil for aeroplanes, the combination of a rigid main part which comprises a main spar, a series of rigid ribs or formers carried by said spar the forward ends of which do not extend as far as the nose or leading edge, and covering surfaces carried by said ribs or formers and extending between said main spar and the rear or trailing edge; and a flexible forward part comprising a series of elastic members carried by the main spar, a rigid nose carried by said elastic members, a series of flexible elements extending between and carried by the main spar and the nose, a series of flexible elements carried by the nose and extending between said nose and said main spar, and covering surfaces carried by said ele- 125 130

ments; and means for varying the degree of flexibility of the forward part of the aerofoil.

4. An aerofoil for aeroplanes comprising
5 a rigid main part which consists of a main
spar, a series of rigid ribs or formers at-
tached to said spar the forward ends of
which do not extend as far as the nose or
leading edge, and covering surfaces carried
10 by said ribs or formers and extending be-
tween said main spar and the rear or trail-
ing edge; and a flexible part consisting of a
series of elastic members carried by the
main spar, a rigid nose carried by said elas-
tic members, a series of flexible elements ex-
tending between and attached to the main
spar and the nose, a series of flexible ele-
ments carried by the nose and extending
between said nose and said main spar, and
flexible coverings carried by said flexible
15 ribs or formers; stops carried by the rigid
ribs or formers forward of the main spar,
and means for adjusting the relative posi-
tions of said stops.
20 5. An aerofoil for aeroplanes comprising
a rigid main part which consists of a main
spar, a series of rigid ribs or formers at-
tached to said spar the forward ends of
which do not extend as far as the nose or
25 leading edge, and covering surfaces carried
by said ribs or formers and extending be-

tween said main spar and the rear or trail-
ing edge; and a flexible part consisting of
a series of elastic members carried by the
main spar, a rigid nose carried by said elas-
tic members, a series of flexible elements ex-
tending between and attached to the main
spar and the nose, a series of flexible ele-
ments carried by the nose and extending
between said nose and said main spar, and
flexible coverings carried by said flexible
ribs or formers; stops carried by the rigid
ribs or formers forward of the main spar,
and means for adjusting the relative posi-
tions of said stops.

30 6. The combination in an aerofoil for aero-
planes of a main spar, a series of rigid ribs
or formers carried by said spar covering
surfaces carried by said rigid ribs or form-
ers and extending between said main spar
and the rear or trailing edge, a series of
35 elastic members carried by said main spar,
a rigid nose carried by said elastic mem-
bers, a series of upper flexible elements ex-
tending between and fixed to said main
spar and said nose, a series of under flexi-
ble elements extending between said nose
40 and said spar and fixed to said nose, cov-
erings carried by said flexible elements and
means for varying the degree of flexibility
of said elastic members.

ALEXANDER ALBERT HOLLE.
